UNITED STATES PATENT OFFICE

2,224,195

TOOL

William J. Parsons, Millers Falls, Mass., assignor
to Millers Falls Company, Greenfield, Mass., a
Corporation of Massachusetts

Application February 4, 1938, Serial No. 188,634

1 Claim. (Cl. 145—61)

This invention relates to tool handles and more particularly to rotatable handles and knobs of the type commonly used on auger braces.

One of the objects of this invention is to provide a knob for an auger brace which is rotatable virtually without friction while requiring a minimum of lubrication.

Another object is to provide a handle for an auger brace having the above stated advantages.

10 A further object is to make it possible to use novel materials in the manufacture of the outer portions of such knobs and handles.

15 A still further object is to provide novel and advantageous means for mounting the name and/or trade-mark of the manufacturer in such tools.

Other objects will appear from what follows.

One embodiment of the invention will now be described, as a non-limiting example, in connection with the accompanying drawing in which:

Fig. 1 is a longitudinal section of the head and handle portions of an auger brace constructed according to this invention;

20 Fig. 2 is an elevation of a brace head showing a way of mounting manufacturer's name and trade-mark; and

Fig. 3 is an elevation showing the reverse side of Fig. 2.

It is one of the purposes of this invention to 30 make possible the use of ornamental materials, such as the well-known transparent colorable condensation resins or other moldable plastics, in the manufacture of frictionless rotating tool parts. Accordingly, head knob 6 and handle 1

35 should be visualized in the drawing as substantially transparent. Quill 8 is provided interiorly with an "Oilite" bronze bearing 9 (as shown in Fig. 1). Quill 8 is held in place by U-shaped key 10 fitting in lateral slots 11 in main or crank

40 shaft 12. At its other end quill 8 rides against washer 13 and ball bearings 14 carried in flanged collar 15. Quill 8 is provided with annular shoulder 16 against which rests metal shell or base plate 17, securely fastened thereto by friction,

45 solder or other suitable means. Knob 6 is secured to the rest of the head by screwing over threaded portion 18 of quill 8 and is bolted to base plate 17 by means of screws 19 in screw holes 20. This construction is extremely simple

50 and requires no further lubrication than a relatively slight amount applied when the tool is initially assembled.

Head knob 6, as shown in Fig. 1, is provided with a tapped hollow central recess 21 and a pair 55 of concentric grooves 22 and 23 cut into but not completely through the head from the bottom or back. Obviously, the number of grooves may vary from that shown in the drawing. Since the material of which head 6 is made is preferably

60 transparent, recess 21 and grooves 22 and 23

are preferably utilized according to this invention for the displaying of manufacturer's name, his trade-mark or other desirable indicia, as shown in Fig. 2. A convenient way of applying such insignia is by gluing, or otherwise securing within the groove, a piece of paper on which are mounted the desired words. Obviously, this feature of the invention is capable of very varied application, but the described construction has the advantages of being initially extremely simple and at the same time as permanent as is the life of the tool itself.

Handle 1 is preferably made of the same material as head 6. It is interiorly provided at each end with "Oilite" bronze bearings 24 for easy 15 rotation on shaft 12, thus giving this portion of the tool the same advantages as described in connection with the head portion. Handle 1 is held in place in conventional fashion by cooperating collars 25, soldered or otherwise secured to shaft 12.

Since certain changes may be made in the above article and different embodiments of the invention could be made without departing from the scope thereof, it is intended that all matter 25 contained in the above description or shown in the accompanying drawing shall be interpreted as illustrative and not in a limiting sense.

It is also to be understood that the following claim is intended to cover all of the generic and 30 specific features of the invention herein described, and all statements of the scope of the invention which as a matter of language might be said to fall therebetween.

Having described my invention, what I claim 35 as new and desire to secure by Letters Patent is:

A brace handle comprising a quill, means to mount said quill rotatably on the brace, said quill having a threaded outer portion and an inner portion of larger diameter forming a shoulder 40 between said portions, an annular backing plate mounted on said quill and rigidly secured against said shoulder, a knob of transparent, colorable, plastic material slightly larger in diameter than said plate and having a tapped hole in one side 45 which is threaded onto said threaded portion of said quill, said knob having a rim around said tapped hole adapted to bear against said plate, the outer edge of said plate being turned towards said knob so as to engage said knob adjacent the circumference thereof, leaving an annular space between said plate and knob intermediate said rim and the circumference of said knob, means acting across the space between said knob and plate to secure said plate to said 55 knob, said knob having a plurality of annular recesses in the side adjacent said plate, and indicia in at least one of said recesses visible through said knob.

WILLIAM J. PARSONS. 60
